UNITED STATES PATENT OFFICE

113,274

DESIGN FOR A DRESS ENSEMBLE

Margaret Michelson, New York, N. Y.

Application December 9, 1938, Serial No. 81,680

Term of patent 3½ years

To all whom it may concern:

Be it known that I, Margaret Michelson, a citizen of the United States, residing at 525 Seventh Avenue, New York, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my new design.

Fig. 2 is the rear view thereof,

Fig. 3 is a front view of the dress unit of my ensemble, and

Fig. 4 is the rear view thereof.

The trim around the edges of the jacket and on the skirt flounce is of embroidery.

I claim:

The ornamental design for a dress ensemble, substantially as shown and described.

MARGARET MICHELSON.
